UNITED STATES PATENT OFFICE.

ARTHUR E. HOBSON, OF PHILADELPHIA, PENNSYLVANIA, ASSIGNOR TO THE HART-FORD STERLING CO., OF PHILADELPHIA, PENNSYLVANIA.

DESIGN FOR A SERVING PLATTER.

Application filed February 27, 1922. Serial No. 914. Term of patent 3½ years.

To all whom it may concern:

Be it known that I, ARTHUR E. HOBSON, a citizen of the United States, residing at Philadelphia, in the county of Philadelphia and State of Pennsylvania, have invented a new, original, and ornamental Design for a Serving Platter, of which the following is a specification, reference being had to the accompanying drawing, forming a part thereof.

Figure 1 is a top plan view of my serving platter and;

Figure 2 is a central longitudinal vertical section through the same.

I claim:

The ornamental design of a serving platter, as shown.

ARTHUR E. HOBSON.
